UNITED STATES PATENT OFFICE

PERLEY RALPH DREW, OF CAMBRIDGE, MASSACHUSETTS, ASSIGNOR TO THE B. F. GOODRICH COMPANY, OF NEW YORK, N. Y., A CORPORATION OF NEW YORK

DESIGN FOR A SHOE TAP

Application filed May 29, 1930. Serial No. 35,841. Term of patent 14 years.

To all whom it may concern:

Be it known that I, PERLEY RALPH DREW, a citizen of the United States, residing at Cambridge, in the county of Middlesex and State of Massachusetts, have invented a new, original, and ornamental Design for a Shoe Tap, of which the following is a specification, reference being had to the accompanying drawing, forming a part thereof.

Fig. 1 is a bottom plan view of a shoe tap showing my new design; Fig. 2 is a longitudinal sectional view on line 2—2 of Fig. 1.

I claim:

The ornamental design for a shoe tap as shown.

PERLEY RALPH DREW.
